TENSION REGULATOR FOR PAPER FEED ROLLS

Conrad J. Kern, Drexel Park, Pa., assignor to The Moore & White Co., Philadelphia, Pa., a corporation of Pennsylvania

Application April 28, 1939, Serial No. 270,617

5 Claims. (Cl. 242—75)

This invention relates to automatic brakes for paper feed rolls and, more particularly, to a means for maintaining a uniform braking resistance to the withdrawal of paper from a roll supplying a press or similar structure to insure proper tension at all times on the sheet withdrawn from the roll.

News presses and corresponding structures which require supply rolls of considerable diameter are usually equipped with what is known as a back-stand upon which the roll is mounted and from which it is drawn to the press or the like. Obviously, the tension at which the paper is removed from the roll is important, particularly in the case of news presses where changes in tension will cause a considerable change in register.

Likewise, obviously, the tension of any fixed diameter brake will vary as the diameter of the roll of paper reduces since the leverage arm represented by the roll radius reduces constantly in ratio to the diameter of the brake. For this reason some means must be provided to compensate for the reduction in diameter of the roll. All such means with which I am familiar fail to take into consideration the fact that such rolls are usually purchased in quantity and stored in such manner that they become flattened at one side.

Important objects of the present invention are the provision of a back-stand including braking mechanism which will compensate for the variation in diameter of the roll and which will not be affected by variations in the shape thereof to any appreciable extent and in which the variation of pressure is determined by a plurality of contact members which are so located that a flattened roll will not affect the braking in the usual manner.

These and other objects I attain by the construction shown in the accompanying drawings wherein, for the purpose of illustration, I have shown a preferred embodiment of my invention and wherein:

Fig. 1 is a side elevation partially broken away and partially diagrammatic illustrating roll tensioning means constructed in accordance with my invention;

Fig. 2 is a plan view thereof; and

Figures 3 and 4 are detail sectional views through valves employed in controlling the braking action.

Referring now more particularly to the drawings, the numeral 10 generally designates one of a pair of bearings for receiving the roll shaft 11 of a paper roll 12. Adjacent the illustrated bear-

ing 10 an outboard bearing 13 is provided, this bearing, together with bearing 10, mounting a shaft 14 which, between the bearings 10 and 13, is equipped with a brake drum 15 having associated therewith a band brake 16 anchored at one end as at 17 and having its opposite end connected at 18 to the piston 19 of a cylinder 20 hereinafter more particularly to be described. Shaft 14 at its inner end is equipped with a gear 21 with which a pinion 22 on roll shaft 11 meshes.

Mounted between a bracket 23 on bearing 10 and a further bearing indicated at 24 and parallel to roll shaft 11 a pair of shafts 25 each having thereon an arm provided with a roll-surface-engaging portion 26 at its free end the arms indicated at 27 and 28 extend in opposite directions about the roll engaging the periphery thereof at points which are well spaced circumferentially. These shafts are geared to one another by gears 29 of equal size and one of the shafts has attached thereto a counterweighted arm 30 so arranged that the counterweight constantly serves to urge the roll-engaging elements 26 into engagement with the surface of roll 12. Likewise, one of the shafts has secured thereto a lever 31 by means of which the arms 27 and 28 may be moved to an open position permitting ready insertion of roll 12 and its shaft 11.

One of the gears 29 meshes with a small pinion 32 on a shaft 33, this shaft likewise bearing a sprocket 34 about which a chain 35 is trained, such chain likewise passing over a second sprocket 36. Beneath one run of the sprocket chain a lever 37 is disposed, this lever being pivoted at 38 at a point adjacent one end thereof and at said end being equipped with an adjustable tensioning means generally designated at 39. The long end or arm of the lever has engaged therewith a weighted roller 40 which is linked at 41 to sprocket chain 35 and it will be obvious that as the sprocket chain is shifted through rotation of arms 27 and 28 and corresponding rotation of the shafts 25 and shaft 33 the effective weight imposed on the long arm of the lever will be varied due to change in position of the roller 40.

The numeral 42 designates a motor driven pump receiving its supply from a sump indicated at 43. The discharge line 44 leads to a simple four-way valve 45 such as that shown in Figure 4 through which the discharge may be directed by conduit 44a or 44b either to the upper or lower end of cylinder 20. An outlet line 46 from this four-way valve leads to sump 43. The discharge line 44 from the pump is equipped with a by-pass

47 having arranged therein a pressure-regulating valve 48 the pressure control of which is varied in accordance with the weighting of the long arm of lever 37. This valve may be of any desired construction, a convenient form being illustrated in Figure 3. In this figure the valve proper, indicated at 48a, is shown as spring seated and as having at the upper end of its stem 48b a roller 48c to engage the under surface of lever 37. The casing 48d of this valve may conveniently include an arm 48e mounting the pivot for lever 37. The extent of opening of the valve is determined by the pressure exerted through lever 37. This discharge line is likewise further provided with a relief valve indicated at 49.

With a roll 12 newly placed in position, the position of the several parts will be substantially as illustrated in Figure 1 of the drawings, pump 42 delivering pressure fluid to the upper end of cylinder 20 (see Figure 4) through valve 45 and conduit 44a and it will be obvious that as the diameter of the roll reduces roller 40 will be shifted along lever 37 to correspondingly vary the pressure exerted by piston 19 on the band brake. Due to the fact that two circumferentially spaced contact elements are provided and these elements will always remain equidistant from the axis of roll 12, if the roll be flattened as indicated by dotted lines at 12a, this will not vary the position of roller 40, thus avoiding the oscillatory action of the pressure-applying member which results when but a single arm is employed. When the roll is to be replaced, valve 45, which is manually actuated, may be shifted to deliver the pressure fluid to the lower end of the cylinder through line 44b and exhaust the fluid from the upper end of the cylinder through line 46. This will release the brake, permitting free running of gear 21 which is, obviously, necessary in installing the new roll and threading the sheet therefrom into the associated machine (not herein shown).

It will also be obvious that the construction illustrated is capable of considerable modification without departing from the spirit of my invention.

I claim:

1. Means for controlling the tension of paper drawn from a roll rotating about a fixed axis comprising a brake for the roll and means to vary the tension of the brake in accordance with variation in diameter of the roll, said means including a shiftable member shifting of which varies the braking resistance of the brake, a plurality of roll-engaging elements adapted to engage the periphery of the roll at circumferentially spaced points, means tending to maintain said elements in engagement with the roll, connections between said elements whereby their roll-engaging portions are maintained at points equidistant from the axis of said roll and a connection between said elements and said shiftable member constructed and arranged to position said member in accordance with the position of said elements.

2. Means for controlling the tension of paper drawn from a roll rotating about a fixed axis comprising a brake for the roll, a plurality of roll-engaging elements adapted to engage the periphery of the roll at circumferentially spaced points, means tending to maintain said elements in en-

gagement with the roll, connections between said elements whereby their roll-engaging portions are maintained at points equidistant from the axis of said roll and a connection between said elements and said brake constructed and arranged to vary the position of said brake in accordance with the spacing of said elements from the axis of the roll.

3. Means for controlling the tension of paper drawn from a roll rotating about a fixed axis comprising a brake for the roll, a plurality of roll-engaging elements adapted to engage the periphery of the roll at circumferentially spaced points, means tending to maintain said elements in engagement with the roll, connections between said elements whereby their roll-engaging portions are maintained at points equidistant from the axis of said roll, a connection between said elements and said brake constructed and arranged to vary the position of said brake in accordance with the spacing of said elements from the axis of the roll comprising a fluid pressure cylinder having a piston the position of which controls the position of said brake, and means to vary the position of the piston in accordance with the position of said elements.

4. Means for controlling the tension of paper drawn from a roll rotating about a fixed axis comprising a brake for the roll, a plurality of roll-engaging elements adapted to engage the periphery of the roll at circumferentially spaced points, means tending to maintain said elements in engagement with the roll, connections between said elements whereby their roll-engaging portions are maintained at points equidistant from the axis of said roll and a connection between said elements and said brake constructed and arranged to vary the position of said brake in accordance with the spacing of said elements from the axis of the roll comprising a fluid pressure cylinder having a piston the position of which controls the position of said brake, and means to vary the position of the piston in accordance with the position of said elements, including a pressure regulating valve and means to load said valve in accordance with the position of said elements.

5. Means for controlling the tension of paper drawn from a roll rotating about a fixed axis comprising a brake for the roll, a plurality of roll-engaging elements adapted to engage the periphery of the roll at circumferentially spaced points, means tending to maintain said elements in engagement with the roll, connections between said elements whereby their roll-engaging portions are maintained at points equidistant from the axis of said roll and a connection between said elements and said brake constructed and arranged to vary the position of said brake in accordance with the spacing of said elements from the axis of the roll comprising a fluid pressure cylinder having a piston the position of which controls the position of said brake, and means to vary the position of the piston in accordance with the position of said elements including a pressure regulating valve, a lever loading said valve and means to vary the lever loading in accordance with the position of said elements.
